(57) **CLAIM**

The ornamental design for a plants-and-flowers planter and growth support, as shown and described.

DESCRIPTION

FIG. 1 is a top-front-left perspective view of a plants-and-flowers planter and growth support showing my new design; FIG. 2 is a bottom-rear-right perspective view thereof; FIG. 3 is a front elevational view thereof; FIG. 4 is a rear elevational view thereof; FIG. 5 is a top plan view thereof; FIG. 6 is a bottom plan view thereof; FIG. 7 is a right elevational view thereof; FIG. 8 is a left elevational view thereof; FIG. 9 is a top-front-left perspective view thereof, wherein the plants-and-flowers planter and growth support is shown in a first assembled configuration; FIG. 10 is a bottom-front-right perspective view thereof; FIG. 11 is a top-rear-left perspective view thereof; FIG. 12 is a bottom-rear-right perspective view thereof; FIG. 13 is a top-front-left perspective view thereof, wherein the plants-and-flowers planter and growth support is shown in a second assembled configuration; FIG. 14 is a bottom-front-right perspective view thereof; FIG. 15 is a top-rear-left perspective view thereof; and, FIG. 16 is a bottom-rear-right perspective view thereof.
